DISPLAY CONTAINER

John D. Clarke, Chicago, Ill., assignor to Chicago
Carton Company, Chicago, Ill., a corporation
of Delaware

Application June 11, 1938, Serial No. 213,112

3 Claims. (Cl. 229—41)

This invention relates to improvements in display containers and more particularly to display containers made of paperboard and which comprise a receptacle for containing merchandise and, frequently, an upstanding back panel having suitable display material printed or otherwise applied thereon.

The main objects of the invention are to provide a display container of the type referred to which will provide an unusually attractive display for selected merchandise; to provide a device of the character indicated which may be completely formed by the maker thereof but folded to flat condition for facilitating storage and shipment thereof; and in general it is the object of the invention to provide an improved display device of the type referred to.

Other objects and advantages of the invention will be understood by reference to the following specification and accompanying drawing (1 sheet) wherein there is illustrated a display device embodying a selected form of the invention.

In the drawing:

Figure 1 is a front elevation of the improved display device in its operative condition.

Figure 2 is a section on the line 2—2 of Figure 1.

Figure 3 is a fragmentary bottom view.

Figure 4 is a front elevation similar to Figure 1 but on a smaller scale and showing the device in collapsed condition.

Figure 5 is a section on the line 5—5 of Figure 4, and

Figure 6 is a plan of a blank from which the device is formed.

The display container illustrated in the drawing is preferably made from a single sheet of suitable paper board stock although it will be understood that if preferred, it may be made from several pieces suitably united, for example, at certain fold lines. In this instance, however, the device is illustrated as being made from a single sheet of material.

As shown in Figure 6, the blank from which the device is formed, includes a bottom forming portion designated 7, a back forming portion 8 and a front portion 9.

The bottom portion 7 is provided with a crease or other fold line 10 extending from side to side thereof.

The back portion 8 is separated from the bottom part 7 by a fold line 11 about which the back may be folded to upright position relative to the bottom part 7.

The front part 9 is separated from the bottom part by creasing 12 constituting a fold line about which said front part 9 may be folded to upright position relative to the bottom portion 7.

The bottom portion 7 is of hexagonal form and is provided at its angular end edges, with flaps such as are designated 13, the same being foldable upwardly relative to the bottom portion on suitable fold lines such as indicated at 14.

The back part 8 is provided with creases 15—15 which extend vertically of the back when it is in operative position relative to the bottom. The creases 15—15 also constitute fold lines which permits side portions 16—16 of the back part to be folded forwardly to fit against the rear-most angular ends of the bottom part, the said ends being coincident with the fold lines 14—14. When the side portions 16—16 are so folded, the adjacent flaps 13 of the bottom are caused to bend upwardly to overlap the lower marginal portions of said back wall parts 16—16.

The front part 9 is divided into outside and inside portions 17 and 18, respectively, by aligned fold lines 19—19 which are connected by a slit 20.

The outer portion 17 may be folded on the fold lines 19—19 downwardly to overlap the outside of the portion 18, thereby forming a double thickness front wall portion. The slit 20 is, in this instance, of arcuate form so that the outer portion of the front wall is provided with an upstanding lip 21 for ornamental or other purposes. Other shapes may, of course, be provided.

The two-ply front wall may then be folded upwardly relative to the bottom part 7 on the fold line 12. Both the inner and outer plies of the front wall are provided with approximately vertically extending fold lines 22—22 and 23—23 which approximately register with each other and facilitate the bending of the sidewise extending portions of the front wall to conform to the foremost angular ends of the bottom part. The lower margins of the inner side portions or wings 24—24 and the lower margins of the outer side portions or wings 25—25 are overlapped on their inner surfaces by the adjacent bottom flaps 13—13 which are turned upwardly relative to the bottom as already explained.

The sidewise extending portions or wings 25—25 of the outer ply of the front wall structure are provided with end extensions 26—26 which are adapted to overlap portions of the sides or wings 16—16 of the back part and to be united thereto by suitable means such as adhesive or staples as indicated at 27.

As shown, the bottom forming edges of the front and back parts and their associated wings or side wall parts, are so disposed that when the blank is set up to form a container, the said edges substantially coincide with the edges of the hexagonal bottom member.

To facilitate packaging, storage and shipment of the display device, it is adapted to be collapsed to flat condition. This is accomplished by folding the bottom upwardly on its fold line 10 (as indicated in Figure 5) and flattening of the front and back parts and their connected side wings. Such flattening is permitted incident to the provision of fold lines, as indicated, between the various sections or panels of the front and back parts.

The bottom part 7 is normally held against upward bending when in operative position by the content of the receptacle.

To support the bottom against downward bending under the weight of the content of the receptacle, supporting means are provided adjacent the opposite ends of said bottom portion. In this instance the supporting means comprises extensions 28-28 on the bottom edges of the side wall parts 25-25. Said extensions 28-28 are foldable on fold lines or creases 29-29 to an inwardly extending position at approximately right angles to said side walls 25-25 so that the extensions will underlie marginal end portions of the bottom member. Said extensions are equipped with ears or tabs 30-30 which are foldable relative to the respective extensions on fold lines 31-31 and separable from the adjacent flaps or extensions 26-26 incident to the provision of slits 32-32. The extensions 28-28 are provided with transversely extending fold lines 33-33.

When the device is set up, the supports 28-28 are folded inwardly and the tabs 30-30 are positioned between the overlapping side wall portions 26-16 (see Fig. 3) and there secured incident to the fastenings 21. The fold lines 33-33 of the supports 28-28 when in operative position, are substantially in alignment with the fold line 10 of the bottom and the fold lines of the side walls which are also in alignment with said fold line 10. Hence, when the structure is collapsed as above explained, the said supports 28-28 will unfold to depending positions substantially in the planes of the respective wall portions from which said supports extend.

The shape of the upper portion of the back part may, if desired, be made to represent an article or otherwise made appropriate to the purpose for which the device is intended.

Changes in the described structure may be made without departing from the spirit of the invention, the scope of which should be determined by reference to the following claims, the same being construed as broadly as possible consistent with the state of the art.

I claim:

1. A receptacle of the class described, comprising a single sheet of paperboard shaped and provided with fold lines to form a bottom member, a back wall part integral with and adapted to be bent upwardly relative to said bottom member, an inside front wall part integral with and adapted to be bent upwardly relative to said bottom member, an outer front wall part integrally connected to said inside front wall part and bendable outwardly and downwardly into overlapping relation thereto, side wall parts extending laterally from said outer front wall part

and adapted to be bent into conforming relation to the side edges of said bottom member for cooperating with said front and back wall parts to form, in effect, a substantially continuous side wall extending upwardly from the periphery of said bottom member, and wings extending laterally from said inside front wall part in overlapping relation to portions of said laterally extending side wall parts.

5 10 15 20 25 30 35 40 45 50 55 60 65 70 75 80 85 90 95

2. A collapsible receptacle of the class described, comprising a one-piece sheet material blank shaped and provided with fold lines to form a bottom foldable upon itself, a back wall connected to a rear edge portion of said bottom and foldable to upwardly extending relation thereto, said back wall being extended laterally to provide side forming wings adapted to be folded to side wall position relative to rearward side edge portions of said bottom, an inner front wall connected to the front edge of said bottom and foldable to upwardly extending relation to said bottom, an outer front wall connected to the upper edge of said inner front wall and adapted to be folded downwardly and outwardly into face to face relation to said inner wall, said outer front wall being extended laterally to provide side forming wings adapted to be folded to side wall position relative to forward side edge portions of said bottom, flaps on certain of said lateral extensions for lapping adjacent end portions of other of said extensions, bottom supports connected to the bottom edges of certain of said lateral extensions and adapted to be folded into bottom supporting position underlying adjacent marginal portions of said bottom, said bottom supports being provided with tabs foldable upwardly into face to face relation to the respective adjacent flaps, and means permanently interconnecting said tabs, flaps and adjacent end portions.

3. A collapsible receptacle of the class described, comprising a one-piece sheet material blank shaped and provided with fold lines to form a bottom foldable upon itself, a back wall connected to a rear edge portion of said bottom and foldable to upwardly extending relation thereto, said back wall being extended laterally to provide side forming wings adapted to be folded to side wall position relative to rearward side edge portions of said bottom, an inner front wall connected to the front edge of said bottom and foldable to upwardly extending relation to said bottom, an outer front wall connected to the upper edge of said inner front wall and adapted to be folded downwardly and outwardly into face to face relation to said inner wall, said outer front wall being extended laterally to provide side forming wings adapted to be folded to side wall position relative to forward side edge portions of said bottom, wings extending laterally from said inner front wall into overlapping relation to portions of said lateral extensions of the outer front wall, flaps on certain of said lateral extensions for lapping adjacent end portions of other of said extensions, bottom supports connected to the bottom edge of certain of said lateral extensions and adapted to be folded into bottom supporting position underlying adjacent marginal portions of said bottom, said bottom supports being provided with tabs foldable upwardly into face to face relation to the respective adjacent flaps, and means permanently interconnecting said tabs, flaps and adjacent end portions.

JOHN D. CLARKE.
